UNITED STATES PATENT OFFICE

2,585,306

BELT LOOP SEWING MACHINE

Joseph Galkin, New York, N. Y.

Application May 31, 1947, Serial No. 751,573

7 Claims. (Cl. 112—2)

1

This invention relates to improvements in sewing machines whereby belt loops are automatically produced in a single operation by mechanism which cuts cloth into strips and folds the strips into belt loop form having inturned edge portions and feeds the belt loops with upper feed dogs placed in a single row.

In my prior Patent No. 2,262,547 I have disclosed mechanism for producing belt loops having edge portions in abutting relation and stitched by two spaced needles which caused two threads to pass through and be visible on the upper and lower surfaces of the belt loops.

I have found that it is a detriment to high productive capacity to make a butt edge junction at the trimmed edges because of the very fine workmanship required to produce a full closure at the butt edge. I have found that by overlapping the belt loop fabric that the blindstitched belt loop is easily made.

An object of this invention is to provide mechanism for producing belt loops in which the stitching is not visible on the normally exposed surface of the fabric and which is produced in a single operation.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a top plan view of a blindstitch sewing machine having my invention applied thereto, the three top feed-dogs being removed to show the strip cutting and belt loop folding mechanism.

Figure 2 is a fragmentary top plan view of the work supporting base of the belt loop machine shown in Figure 1, on an enlarged scale, two top feed-dogs being in operative position.

Figure 3 is a top plan view of the belt loop mechanism, the work supporting base of the belt loop mechanism being removed.

Figure 4 is a cross-sectional view, the section being taken as on line 4—4 in Figure 3.

Figure 5 is a front elevation of the sewing machine.

Figure 6 is a top plan view of the presser foot.

Figure 7 is a top plan view of a work clamp which cooperates with the bottom of the presser foot.

Figure 8 is a side elevation showing three top feed dogs mounted in coacting relation.

2

Figure 9 is a perspective view of the folder.

Figure 10 is a perspective view of a finished belt loop on an enlarged scale.

In the illustrated embodiment of the invention, the numeral 10 indicates a hollow frame of a sewing machine embodying my invention and which comprises a base 11 having a standard 12 extending upwardly along the front end of the base 11, a post 13 which extends upwardly from the rear right hand corner of the base, a horizontal arm 14 which extends laterally from the upper end of the post 13 and overhangs the left hand edge of the base 11 and a horizontal arm 15 which extends forwardly from the overhanging end of the arm 14.

The forward end of the arm 15 terminates at a point considerably in the rear of the standard 12. The horizontal arms 14 and 15 and the supporting post 13 are hollow.

Journalized in the horizontal arm 14 is a rotary main shaft 17 having a combined driving pulley and hand wheel 18 fixed to its right hand end portion. Journalized in the forwardly extending horizontal arm 15 is an oscillatory needle shaft 19.

The needle shaft 19 is oscillated from the main shaft 17 by an eccentric on the main shaft which drives a vibratory connection on the needle shaft, as is well known in the art.

As shown in Figure 4 the shaft 19 extends forwardly beyond the free end of the arm 15. Fixed to the projecting end of the shaft 19 is a needle arm 20 to which a curved needle 21 is attached by a clamp 22.

Cooperating with the needle 21 to form a line of single thread blind stitches, is a looper 23 which is fixed to a looper bar 24 pivotally supported as at 25 on the arm 15. The looper bar 24 is actuated from the main shaft 17 by a connection comprising a universal joint on the looper bar and a crank pin angularly positioned at one end of the main shaft (not shown).

A stationary presser foot 30 is disposed below the needle 21 and also below the looper 23. The presser foot is detachably connected to the arm 15 through the medium of a fork 31 which is formed on the rear end of the presser foot and which is secured by screws 32 to the end face of the arm 15.

Journalized on a horizontal pivot shaft 35 at the upper end of the standard 12 is a work support 36 which is normally disposed in a substantially horizontal plane. The support 36 has a straight rear edge 37 which is in rear of the path of needle oscillation. The support 36 is formed at its left rear corner with a reduced extension 38 which projects towards and below the presser foot 30.

In order to yieldably retain the work support 36 in a substantially horizontal plane, and also to provide means for adjusting the plane of the work support 36 relative to the presser foot 30 there is provided the following mechanism:

The work support 36 is provided at its front face with a downwardly extending flange 39 which is positioned in front of the standard 12 of the frame 10, as shown in Figure 5.

The flange 39 carries an adjusting screw 40 and a lock nut 41. The screw 40 extends into contacting relation with the frame 10 and maintains the upper surface of the pivoted work support 36 in a horizontal plane. To maintain this horizontal position of the work support 36 there is provided a rod 42 fixed in the flange 39 and urged toward the rear of the frame 10 by a coil spring (not shown).

This spring tends to swing the work support 36 upwardly relative to the presser foot 30. The screw 40 limits the upward swinging movement of the work support 36 relative to the presser foot.

A foot treadle 45 has a horizontal extension 46 rotatably mounted in bearings 47. An arm 48 is fixed to the extension 46 by a screw 49 and carries a link 50 which is in engagement at its upper end with the free end of the pivotally mounted work support 36.

When the operator presses his foot against the treadle 45, the arm 48 swings the work support 36 about the pivot 35.

The sewing machine comprises means for projecting a ridge of fabric upwardly through the stationary presser foot 30 into needle penetrating position during each cycle of operation.

The ridge of fabric is projected by an oscillatory finger 51 fixed to a rock shaft 52 which is suitably journaled in bearings in the work support 36. The rock shaft 52 is oscillated from the main shaft 17 through the medium of a driving eccentric 53 fixed to the main shaft 17. A strap link 54 has one end fitting around the eccentric 53 and the other end pivotally connected to the lower end of an arm 55 fixed to the rock shaft 52.

The needle 21 oscillates in a fixed path of travel in a needle groove 60 above an opening 61 formed in the presser foot 30. The oscillatory finger 51 projects into the opening 61 of the presser foot when forming and positioning the ridge of fabric upwardly into the path of the needle.

As best shown in Figure 6, the presser foot 30 comprises a presser-finger 62 pivotally mounted on a pin 63 and pressed down by the free end portion 64 of a coil spring 65 which is suitably fixed on a screw 66 in the presser foot.

The presser-finger 62 is mounted on the presser foot 30 at the forward end thereof and at the right hand side of the opening 61 and includes a laterally extending portion 67 which overhangs the oscillatory finger 51. The portion 67 is disposed in front of the path of the needle 21.

Figure 7 is a top plan view of a work clamp or work support finger 68 which cooperates with the bottom of the presser foot 30 to clamp the ridge of fabric therebetween. The ridge projects upwardly through a slot 69 in the work clamp 68 and through the opening 61 in the presser foot.

The work clamp 68 is pivotally mounted on a screw 70 and moves up and down and is spring-pressed towards the presser-foot 30 by a spring 56 connected to a lever 57 pivotally mounted on the screw 58. The lever 57 is pivotally connected by the screw 70 to the work clamp 68 which holds

the fabric against the thrust of the needle. The work clamp 68 has two upwardly extending side bars 71, 72 forming a passageway therebetween for the folded belt loops. The above mechanism provides a resilient mounting for the work clamp 68. The usual resilient mounting of the work clamp 68 is shown in Patent No. 2,157,032.

The invention is particularly directed to a combination of mechanisms operating upon scraps of cloth for automatically forming in a single operation belt loops having flat and superposed edge portions. The invention comprises a trimming mechanism 73 for trimming two fabric edges so as to prepare a strip of predetermined width, and a folder 74 for folding the strip into belt loop form and directing the same to the stitching mechanism for stitching the belt loop.

The invention also provides a front top feed-dog 75 having a forward portion of rectangular form for feeding the strip through the trimming mechanism, and having an integral rear portion 75' of triangular form for feeding the cut strip to and through the folder 74 and to the stitching machine.

The forward portion of the front top feed-dog 75 feeds the fabric to and through movable shear blades 77, 77' held in carriers 78, 78'. The movable blade carriers are slidably mounted on a rock shaft 79. As shown by dotted lines in parts 78 and 78', Figure 3, the carriers 78, 78' are slidably mounted on the shaft 79 by a key 80 and are resiliently pressed by coil springs 81 in the direction of the stationary shear blades 87.

The springs 81 react against collars 82 fixedly mounted on the shaft 79. The stationary shear blades 87 are held in properly spaced cutting relation by being held in a blade carrier 83 of the desired width. The movable shear blades 77, 77' thus cooperate with the stationary shear blades 87 to cut a fabric strip of predetermined width.

The movable shear blades 77, 77' are given substantially vertical movements by the carriers 78, 78'. The carriers slidably engage the elongated key 80. The key is held in fixed parallel relation with the rock shaft 79 by being held in an arm 84 fixed to the shaft. An arm 85 is fixed to one end of the shaft 79, and is pivotally connected to a vibrating connection 86 operated by an eccentric 88 on the main shaft 17. As the main shaft 17 rotates, the rock shaft 79 actuates the movable shear blades 77, 77' once for each revolution of the main shaft.

As shown in Figures 3 and 4, the belt loop forming mechanism comprises an intermediate top feed-dog 76 which serves for feeding the folded strip of fabric through the passageway between the side bars 71, 72 in the work clamp 68 and to the ridge forming element or oscillatory finger 51. The feed-dog 76 is secured by a screw 93 at one end of an extension feed bracket 94. The extension feed bracket 94 is secured to a sewing machine feed-bar 95 which is given four-motion feeding movements through a mechanism (not shown) but which is well known in the art.

The front top feed-dog 75 for feeding the scrap or strip fabric between the movable shear blades 77, 77' is pivotally mounted on a screw 101 passing through the forward portion 102 of the feed bracket 94. The front top feed dog 75 is secured to a carrier 103 which is pivotally mounted on the screw 101 in the forward portion 102 of the extension feed bracket 94. A coil spring 103 is mounted on the screw 101 and is secured at

one end against a hub 104 of the feed bracket 94 and is in tensioned engagement at the other end against a screw 105 in the carrier 100. The coil spring 103 serves to press the front top feed-dog 75 against the upper surface of the blade carrier 83 for the stationary blades 87, and in pressure contact with the work. The upper surface of the blade carrier 83 is at the level of a raised front extension or belt loop work support 107 in front of the work support 36.

The front top feed-dog 75 has feeding teeth extending transversely across the entire lower surface thereof. These teeth face in the same direction as the teeth on the intermediate top feed-dog 76, and in the same direction as the teeth on the rear top feed-dog 89, Figure 8.

As best shown in Figure 3, it will be seen that the front top feed-dog 75 is considerably wider than the intermediate top feed-dog 76. In practice, the front feed-dog 75 feeds strip fabric cut to the size of a blank belt loop, while the intermediate feed-dog 76 feeds fabric folded in belt loop form.

The intermediate top feed-dog 76 comprises a rectangular front portion 90 and a reduced rear portion 91 of a size small enough to operate in a slot 92 in the presser-finger 62.

As shown in Figure 4, it will be seen that the movable blades 77 have substantially horizontal cutting edges. These blades are given downward cutting movements against the work. It will be seen that when the top feed-dog is feeding, it presses on the work, while the movable blades are clear of the work. The material worked upon is contacted successively by the top feed-dog or by the movable blades.

In my prior patent, I have disclosed a folder having a tongue about which the cut belt loop strip has its side edges folded underneath the strip.

In the disclosure herewith, the folder 74 is without any tongue. As shown in Figure 9, the folder 74 comprises upwardly and inwardly turned side edge portions 108, 109. The far end of the edge portion 109 is positioned higher and in overlapping relation with the far end of the edge portion 108, that is, at the outlet end 110, Figure 1.

The folder 74 has a triangular passageway 111 which causes an overlapping of the edges of the belt loop 112, Figure 10. The finished belt loop 112 is made with single thread chain stitches 113.

Under certain conditions it is desirable to feed a tape 114 into the belt loop 112 to facilitate the chaining of the sewing thread. This tape is fed through a slot 115 in the front top feed-dog 75 and rearwardly underneath the triangular portion 75' of the front top feed-dog. The tape provides a positive means for feeding the finished belt loops when passing beyond the needle without breaking the thread.

In accordance with the patent statutes I have described and illustrated the preferred embodiment of my invention, but it will be understood that various changes and modifications can be made therein without departing from the spirit of the invention as defined by the appended claims.

I claim:

1. In a mechanism for simultaneously trimming both edges of a fabric strip and top feeding and finishing belt loops having flat and superposed edge portions in a single operation, the combination with a sewing machine having a work supporting base, a head, a presser foot

supported by said head and a curved needle and means for forming blindstitch stitching, an arm reciprocally mounted in said head and having a four-motion feeding movement and carrying a feed-dog in the rear of said needle, front and intermediate top feed-dogs placed one behind the other and being fixed to said rear feed-dog carrying arm and being mounted for four-motion feeding movements in front of said needle, means for pivotally mounting and resiliently downpressing said front top feed-dog, reciprocatory shear blades mounted on a shaft positioned below said work supporting base, said blades being respectively positioned on opposite sides of said forward top feed-dog for cutting a strip of fabric of predetermined width, a work clamp below said presser foot having two rigid side bars forming a fixed guideway centrally and lengthwise thereof, a folder for folding both side edges of said sheared strip of fabric above said strip into superposed relation, said folder having a converging passage in its upper wall, said reciprocatory shear blades coating with stationary blades secured to opposite faces of a stationary blade carrier having a flat upper surface, said front top feed-dog being pivotally mounted on a pivot carried by said reciprocating arm, said intermediate top feed-dog being mounted in the rear of said folder passage for feeding the folded fabric through said folder and directly to said needle.

2. In a mechanism for simultaneously trimming both edges of a fabric strip and top feeding and finishing belt loops having flat and superposed edge portions in a single operation, the combination with a sewing machine having a work supporting base, a head, a presser foot supported by said head and a curved needle and means for forming blindstitch stitching, an arm reciprocally mounted in said head and having a four motion feeding movement, said arm carrying a top feed-dog in the rear of said needle, front and intermediate top feed-dogs placed one behind the other and being fixed to said rear feed-dog carrying arm and being mounted for four motion feeding movements in front of said needle, means for pivotally mounting and resiliently downpressing said front top feed-dog, reciprocatory shear blades mounted on a shaft positioned below said work supporting base, said blades being respectively positioned on opposite sides of said forward top feed-dog for cutting a strip of fabric of predetermined width, a folder for folding both side edges of said sheared strip of fabric above said strip into superposed relation, said folder having a converging angularly directed passage in its upper wall, a work clamp below said presser foot having two rigid side bars forming a guideway centrally and lengthwise thereof for guiding folded belt loops, said reciprocatory shear blades coating with stationary blades secured to opposite faces of a stationary blade carrier having a flat upper surface, said front top feed-dog being pivotally mounted on a pivot carried by said reciprocating arm in front of said intermediate top feed-dog, said intermediate top feed-dog being mounted in the rear of said folder passage for feeding the folded fabric through said folder and directly to said needle.

3. In a mechanism for simultaneously trimming both edges of a fabric strip and top feeding and finishing belt loops having flat and superposed edge portions in a single operation, the

combination with a sewing machine having a work supporting base, a head, a presser foot supported by said head and a curved needle and means for forming blindstitch stitching, an arm reciprocally mounted in said head above said work supporting base and having a four-motion feeding movement, said arm carrying a top feed-dog in the rear of said needle, front and intermediate top feed-dogs placed one behind the other and being fixed to said arm and being mounted for four-motion feeding movements in front of said needle, means for pivotally mounting and resiliently downpressing said front top feed-dog, reciprocatory shear blades mounted on a shaft positioned below said work supporting base, said blades being respectively positioned on opposite sides of said forward top feed-dog for cutting a strip of fabric to a predetermined width, a folder for folding both side edges of said sheared strip of fabric above said strip into superposed relation, said folder having a rearwardly converging passage in its upper wall, a work clamp below said presser foot having two rigid side bars forming a guideway centrally and lengthwise thereof for guiding folded belt loops, said reciprocatory shear blades coacting with stationary blades secured to opposite faces of a stationary blade carrier having a flat upper surface, said front top feed-dog being pivotally mounted on said reciprocating arm in front of said intermediate top feed-dog, said intermediate top feed-dog being mounted in the rear of said folder passage for feeding the folded fabric through said folder and directly to said needle.

4. In a mechanism for simultaneously trimming both edges of a fabric strip and top feeding and finishing belt loops having flat and superposed edge portions in a single operation, the combination with a sewing machine having a work supporting base, a head, a presser foot supported by said head and a curved needle and means for forming blindstitch stitching, a feed arm reciprocally mounted in said head above said work supporting base and having a four-motion feeding movement, said arm carrying a top feed-dog in the rear of said needle, front and intermediate top feed-dogs placed one behind the other and being fixed to said arm and being mounted for four-motion feeding movements in front of said needle, means for pivotally mounting and resiliently downpressing said front top feed-dog, reciprocatory shear blades mounted on a shaft positioned below said work supporting base, said blades being respectively positioned on opposite sides of said forward top feed-dog for cutting a strip of fabric to a predetermined width, a folder for folding both side edges of said sheared strip of fabric above said strip and into superposed relation, said folder having a rearwardly converging passage, a work clamp below said presser foot having two rigid side bars forming a guideway therebetween and centrally and lengthwise thereof for guiding folded belt loops, said reciprocatory shear blades coacting with stationary blades secured to opposite faces of a stationary blade carrier having a flat upper surface, said front top feed-dog being pivotally mounted on said reciprocating arm in front of said intermediate top feed-dog, said front top feed-dog having a rectangular front portion for feeding flat strip fabric between said shear blades and having a triangular rear portion for feeding the fabric through said folder, said intermediate top feed-dog being mounted in the rear of said folder

passage for feeding the folded fabric through said folder and directly to said needle.

5. In a mechanism for trimming both edges of a fabric strip and finishing blindstitched belt loops having superposed edge portions, the combination with a sewing machine having a work supporting base, a head, a presser foot supported by said head, a curved needle and means for forming blindstitch stitching, a feed arm reciprocally mounted in said head above said work supporting base and having a four-motion feeding movement, said arm carrying a top feed-dog in the rear of said needle, top feed-dog means fixed to said arm and mounted for four-motion feeding movements in front of said needle, stationary and reciprocatory shear blades respectively positioned to cut a section of fabric to a predetermined width, a triangularly shaped folder having curved side edges for folding the side edges of said strip of fabric into superposed relation, said folder having a rearwardly converging passage, a work clamp below said presser foot, said front top feed-dog means having a rectangular front portion for feeding flat strip fabric between said shear blades and having a triangular rear portion for feeding the fabric through said folder.

6. In a mechanism for trimming both edges of a fabric strip and finishing blindstitched belt loops, the combination with a sewing machine having a pivoted work supporting base, a head, a presser foot supported by said head, a curved needle and means for forming blindstitch stitching, a feed arm reciprocally mounted in said head above said work supporting base and having a four-motion feeding movement, said arm carrying a top feed-dog in the rear of said needle, top feed-dog means fixed to said arm and mounted for four-motion feeding movements in front of said needle, stationary and reciprocatory shear blades respectively positioned to cut a section of fabric to a predetermined width, a triangularly shaped folder having curved side edges for folding the side edges of said strip of fabric into superposed relation, said folder having a rearwardly converging passage, a work clamp below said presser foot, a stationary blade carrier, said reciprocatory shear blades coacting with stationary blades secured to opposite faces of said stationary blade carrier, said front top feed-dog means having a rectangular front portion for feeding flat strip fabric between said shear blades and having a triangular rear portion for feeding the fabric through said folder.

7. In a blindstitch belt loop sewing machine having a curved needle and a feed arm and a feed-dog carried thereby for four-motion feeding movements in the rear of said needle, a work support in front of said needle, a top feed means attachable to said feed arm and including a front top feed-dog positioned in front of said needle, and means for resiliently downpressing said front top feed dog against said work support, for four motion feeding movements thereon.

JOSEPH GALKIN.
